UNITED STATES PATENT OFFICE

RHEA R. CRAVENS, OF BIG SPRING, TEXAS

ELECTRIC WELD REMOVER

Application filed June 18, 1928. Serial No. 286,329.

The present invention relates to an improved device to be hereinafter known as an electric weld remover, and it has more particular reference to a structure employed for 5 removing the consolidated weld deposits from boiler tube beads which have become loose and leaky and need rewelding.

Briefly, the structure embodies an especially cast or made body constituting a mounting 10 for a plurality of adjustable cutters, and a series of freely rotatable guides and anti-friction elements. This body is provided with a coupling adapted to telescopically fit into a driving chuck and it is bored for passage 15 for a tapered roller adjusting spindle.

The novelty is predicated upon the efficient organization of the parts which cooperates in permitting the device to fulfill the requirement of a device of this class, in a dependable 20 and positive manner.

Other features and advantages of the invention will become more readily apparent from the following description and drawings.

In the drawings:

25 Figure 1 is a side elevational view of a device constructed in accordance with the invention, showing the complete organization of parts ready for use.

Figure 2 is a perspective view of the tool 30 holder or chuck.

Figure 3 is a perspective view of the adjustable spindle.

Figure 4 is a perspective view of one of the 35 grooved guide rollers for engagement with the bead on the end of the tube.

Figure 5 is a longitudinal sectional view through Figure 1, showing the internal association of parts more plainly.

Figure 6 is a cross section taken approximately 40 upon the plane of the line 6-6 of Figure 5, looking in the direction of the arrows.

Figure 7 is an end view of Figure 1, looking in a direction from left to right.

45 Figure 8 is a cross section on the line 8-8 of Figure 5.

Figure 9 is a group perspective view of the cutter carrying body.

50 Figure 10 is an enlarged view, taken on the line 10-10 of Figure 5.

Figure 11 is a perspective view of a retaining ring.

Referring now to the drawings by reference numerals, it will be observed that 12 designates generally the improved cutter and 55 roller carrier or body. As before intimated, it is in the form of a casting 13, including a substantially disc like part having a forwardly projecting centering neck 14, on the end of which is a retaining washer 15. As 60 shown in Figure 11, this washer is provided with small holes 16 for passage of the retaining bolt 17 and is provided with elongated slots 18, at its circumferentially spaced points, for adjustable reception of the journals on 65 the ends of the internal guide rollers 19. Incidentally these rollers fit within the tube and are disposed in rolling contact with the interior of the tube. The part 13 is formed at the inner end of the neck 14 with an annular 70 groove having a bevelled flange 20 for confining a cutter retaining spring 21. This spring is of the endless coiled type and engages the cutting element 22, as shown plainly in Figure 5. These cutting elements are mounted 75 in notches in the periphery of the body 13, as is evident from Figure 9. Cooperating with the cutters are grooved anti-friction and guide rollers 23, having their stem portions 24 extending through radial holes in 80 the body. Incidentally the body is longitudinally bored and these stems extend into the bore as shown in Figure 5.

Cooperating with the grooved rollers 23 are the aforesaid rollers 19. Both sets of 85 rollers are adjusted for extensive action produced by the presence of the longitudinally slidable tapered spindle or wedge pin 25. This pin has a head on its inner end as at 26, and the head cooperates with a pressure spring 27, located within the tool holder or socket 28. This socket is provided with the customary driving shank 29 to be operatively associated with an air motor or the like. It will be noted that the polygonal end 90 extension 30 of a disc 31 fits telescopically in the socket 28. This disc is bolted to the body 13, and carries adjustable bolts 32, for the cutter 22.

As before intimated the device is employed 100

for chipping and scraping off the consolidated metal deposits or electric weld from around the bead of a boiler tube. Hence, it is obvious that the neck 14 of the carrier 12 is inserted into the tube, whereby the rollers 5 19 come into contact with the inner surface of the tube. The grooved rollers 23 engage the bead on the outer end of the tube. Then, when the device is set into rotation by appropriate means, the cutters act on the metallic deposit and scrape it off cleanly, and leave a true surface for rewelding. It is evident that the spring pressed wedge pin 25 comes into adjusting engagement with the rollers 19 and 23, adapting them to the particular diameter of the tube being acted on, so that the cutters 22 resting upon the rollers 23 are also adjustably affected, whereby the cutters may be adjusted with respect to the diameter of the tube being acted upon. 10 20 It is thought that by considering the description in connection with the drawing, a clear understanding of the invention will be had. Therefore a more lengthy description is regarded unnecessary.

25 Minor changes in the shape, size and rearrangement of parts may be resorted to, within the invention as set forth in the accompanying claims.

30 I claim:

1. An electric weld remover comprising a body having a circumferential groove, and a centralized projection to fit telescopically within a boiler tube, a set of anti-friction rollers carried by said projection for engagement with the inner bore of the tube, a second set of anti-friction rollers carried by said body and adapted to engage the head of the boiler tube, said second set of anti-friction rollers having their axes at right angles to 35 40 the axes of the first mentioned set of anti-friction rollers, cutters mounted on said body and arranged within said groove, in operative relation to said second set of anti-friction rollers, and a spring arranged in said groove and bearing against said cutters for urging said cutters into engagement with the last referred to series of anti-friction rollers.
- 50 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

adjusting stems extending through openings in said carrier into the bore of said carrier, and a spring pressed tapered wedge pin extending through the bore of said carrier for engagement with said stems, and with the first mentioned rollers simultaneously to accommodate the tube acted upon, and the stems at their outer ends adapted to contact with said cutters for effecting an adjustment of said cutters simultaneously with the outward radial movement of all of said rollers.

3. A weld remover for tubes, comprising a carrier including a circular body having peripheral notches and an endless groove, said body being centrally bored and formed with a centralized pilot extension for entering the tube, an annular series of anti-friction rollers carried on said extension, means for mounting said rollers on said extension for radial movement with respect to said extension for engagement with the inner bore of the tube, a series of grooved anti-friction rollers having their axes at right angles to the axes of the first mentioned rollers whereby said last mentioned rollers may engage the bead of the tube, said grooved anti-friction rollers including stems extending slidably through openings in said body, the inner ends of the stems being controlled intermediate the first mentioned rollers, cutters mounted in said notches, an annular coil spring in said groove for yieldably urging said cutters into engagement with the outer ends of said stems, and a spring pressed wedge pin movable longitudinally in the bore of said body for engagement with the first mentioned rollers and the inner ends of said stems whereby all of said rollers and said cutters may be simultaneously adjusted to accommodate the tube.

4. A weld remover for tubes, comprising a carrier including a circular body having peripheral notches and an endless groove, said body being centrally bored and formed with a centralized pilot extension for entering the tube, an annular series of anti-friction rollers carried on said extension, means for mounting said rollers on said extension for radial movement with respect to said extension for engagement with the inner bore of the tube, a series of grooved anti-friction rollers having their axes at right angles to the axes of the first mentioned rollers whereby said last mentioned rollers may engage the bead of the tube, said grooved anti-friction rollers including stems extending slidably through openings in said body, the inner ends of the stems being controlled intermediate the first mentioned rollers, cutters mounted in said notches, an annular coil spring in said groove for yieldably urging said cutters into engagement with the outer ends of said stems, and a spring pressed wedge pin movable longitudinally in the bore of said body for engagement with the first mentioned rollers

and the inner ends of said stems whereby all of said rollers and said cutters may be simultaneously adjusted to accommodate the tubes, a disk bolted to said body portion and including a coupling extension, a tool holder 5 embodying a socket, said coupling extension fitting into said socket, and said spring actuating wedge pin extending through said extension and having one end receivable in the socket of said tool holder.

10 In testimony whereof I affix my signature.
RHEA R. CRAVENS.
